SEALING-IN APPARATUS

Henry W. Jacobsen, Cleveland Heights, Ohio, as
signor to General Electric Company, a corpora-
tion of New York

Application June 22, 1944, Serial No. 541,519½

14 Claims. (Cl. 49—2)

1

My invention relates in general to a sealing apparatus for electric lamps and similar devices such as fluorescent lamps, and more particularly to a work-supporting spindle construction for such sealing apparatus. The invention is of particular utility in connection with sealing apparatus of the type employing gas sealing fires, such as described and claimed in copending U. S. application Serial No. 465,008, F. J. Malloy, filed November 9, 1942, which issued as Patent No. 2,434,664, January 20, 1948.

In the sealing of the amounts to the ends of fluorescent lamp envelopes, it is customary to abut one end of the envelope against the flare portion of the mount stem and then heat the contiguous portions of the envelope and flare until they become fused and sealed together. One of the difficulties encountered in making such a seal is the sagging of the softened outer portions of the glass flare immediately inward of the seal. Such sagging of the flare produces a sagged or "drooped" seal which is very weak and readily cracks when subjected to the compressive force applied thereto (due to temperature changes) by the base which is subsequently cemented to the end of the envelope around the seal. To therefore insure the production of a good seal sufficiently strong to withstand the compressive force exerted thereon by the base, it is desirable to eliminate sagging of the flare inwardly of the seal and produce a seal in which the glass of the flare extends diagonally upward in a straight line right from the seal, i. e. in true conical shape.

One object of my invention is to provide an improved sealing apparatus for sealing glass stems to the ends of envelopes for fluorescent lamps and similar electrical devices.

Another object of my invention is to provide apparatus for producing a mechanically strong and gastight seal between a glass flare and an end of a glass tube.

Still another object of my invention is to provide apparatus for sealing a glass flare to an end of a glass tube to produce a seal wherein the glass of the flare extends in a straight line from the seal in true conical shape.

Further objects and advantages of my invention will appear from the following description of a species thereof and from the accompanying drawing in which:

Fig. 1 is a diagrammatic plan view of sealing apparatus comprising my invention; Fig. 2 is a vertical section through one of the heads of the apparatus comprising my invention with the head spindle shown in a position rotated 90 degrees

from its normal loading position at station A; Fig. 3 is a diagrammatic perspective view of the spindle-operating cam tracks of the apparatus comprising my invention; Figs. 4 and 5 are enlarged vertical sections through the head spindle showing the positions of the various spindle parts when the head is located at stations A and E, respectively; Fig. 6 is a vertical section similar to Figs. 4 and 5 but showing the positions of the various spindle parts when the head is located just beyond station J, at the highest point of the seal-upsetting cam located immediately beyond said station; and Fig. 7 is an enlarged fragmentary section of one end of a fluorescent lamp which has been sealed by the apparatus comprising my invention.

Referring to the drawing, the invention is there shown as applied to a fluorescent lamp sealing machine of the gas-fire type disclosed and claimed in the previously mentioned U. S. Patent No. 2,434,664 of F. J. Malloy. The said machine comprises, in general, a turret or carrier 1 provided with a plurality (16) of heads 2 located at uniformly spaced intervals around the periphery of the turret. The turret 1 is supported on a vertical shaft 3 journalled in the machine bed 4 and is intermittently rotated in a counterclockwise direction to successively index or advance the heads 2 to a plurality of work stations A to Q corresponding in number to the number of heads. The indexing means for the turret 1 may be of any well-known type, such as that illustrated in U. S. Patent No. 1,742,153, Stiles et al., and comprising a rotating drum-type cam 5 mounted on a horizontal drive shaft 6 and engaging with a plurality of rollers 7 depending from a disc 8 fastened to the turret support shaft 3.

The heads 2 are each arranged to support a conventional fluorescent lamp mount 9 and glass envelope 10 in proper sealing relation to one another with the tubular envelope disposed vertically and its lower end resting on the flare of the mount stem. The mount 9 illustrated in the drawing is of the type shown in U. S. Patent 2,312,245, J. Flaws, and comprises a glass stem 11 having a flare portion 12, and a pair of lead-in wires 13 sealed through the stem and connected at their inner ends to a filamentary coil electrode 14 coated with a suitable electron-emissive material, such as an alkaline earth oxide, like barium oxide for instance.

The general operation of the machine is similar to that described in the previously mentioned U. S. Patent No. 2,434,664, the mount 9 and the envelope 10 being first loaded into the head

2 at the loading stations A and B after which the turret indexes the head through idle station C and thence through a series of successive heating station D to O inclusive where the stem flare 12 and the lower end of the envelope 10 are heated by gas fires at said stations to thereby fuse and seal the glass parts together. After it has passed through a cooling station P, the sealed envelope and mount are then removed from the head 2 at the unloading station Q.

Each of the heads 2 comprises a vertical spindle 15 rotatably mounted in roller bearings 16 supported in a housing 17 on the turret 1. The spindle 15 according to the invention comprises outer and inner sleeves 18 and 19, respectively, which extend down through another sleeve 20 journaled in the roller bearings 16. The said sleeve 20 supports a suitable bulb holder 21, for holding the tubular lamp envelope 10 in a vertical position in alignment with, and resting on the flare 12 of the lamp mount 9. The holder 21 is fastened to a pair of vertical side rods or posts 22 located on opposite sides of the spindle axis and extending upward from, and secured to, a flange 23 integral with the spindle sleeve 20. The holder 21, which may be of the type described and claimed in my copending application Serial No. 541,599½ filed of even date herewith, comprises spring-pressed jaws 21' and 21" which grip the tubular lamp envelope 10 very tightly so as to prevent vertical sliding of the envelope in the holder in the event a lifting force is applied to the envelope, even though the lifting force be of considerable magnitude.

To insure the heating and sealing together of the glass parts uniformly around their periphery, the spindles 15 are continuously rotated during the interval when they are positioned at each of the heating stations D to O inclusive. For this purpose, each of the spindles is provided with a pulley 24 which is secured to the lower end of the spindle sleeve 20 and is continuously engaged by a moving belt 25 from the time just before it reaches station D until just after it indexes away from station O.

To permit unloading and loading of the heads 2, the spindles 15 are locked in a definite rotative position at station P and are thereafter continuously maintained in such rotative locked position until just after the heads index away from station C. For this purpose, each spindle pulley 24 is provided with a depending roller 26 which rides in an arcuate groove or channel 27 provided by a guide track 28 supported by brackets 29 mounted on the table portion 30 of the machine bed 4. Upon arriving at station P, each spindle 15 is rotated to and is held in proper rotative position for subsequent entry of the roller 26 into the guide channel 27 by means of a rotating friction wheel 31 which frictionally engages with and rotates a drum 32 on the pulley 24 until the roller 26 strikes against the end of a pivotal stop or latch 33 located at the front end of the guide track 28. The stop latch 33 is held in its normal roller-engaging position, against a stop pin 34, by the action of a tension coil spring 35. As soon as the spindle 15 begins to index away from station P, the roller 26 enters and rides in the channel 27 formed by the guide track 28 thus continuously locking the spindle against rotation until the roller 26 clears the rear end of the guide track 28 at a point intermediate stations C and D, the spindle then being free to rotate once again.

The upper end of the outer spindle sleeve 18

is provided with an outwardly extending flange preferably in the form of a separate collar 36 suitably secured to the said sleeve, as by screws 37. The collar 36 normally supports the lamp mount 9 from the time it is first loaded into the head 2 at the loading stations A and B until just after the head indexes away from the first heating station D. During this period, the collar 36 is constantly maintained at a predetermined mount-positioning elevation by means of an arcuate cam track 38 which underlies and engages a shoe 39 on the lower end of the outer sleeve 18.

As shown in Figs. 3 and 4, the collar-positioning cam track 38 is supported on the table portion 30 of the machine bed 4 and it extends from a point intermediate stations P and Q through stations A, B, C and around to a point intermediate stations D and E. The opposite ends of the collar-positioning track 38 are tapered to provide an ascending upper surface or lift 40 at the front end of the track and a descending upper surface or drop 41 at the rear end of the track. The forward taper or lift 40 terminates at a point just before the first loading station A while the rear taper or drop 41 begins at a point just beyond station D. Thus, an intermediate uniformly-elevated track portion 42 is provided extending from a point just before station A and continuing around to a point just beyond station D. As shown in Figs. 2 and 4, the cam track 38 is offset a slight amount to one side (preferably outwardly) of the spindle axis so as not to interfere with that portion of the inner spindle sleeve 19 which projects down beyond the lower surface of the shoe 39 on the outer sleeve 18.

The outer spindle sleeve 18, when not supported in its elevated mount-loading position (Fig. 4) by the cam or shoe track 38, is supported in a slightly lowered or "sealing" position (Fig. 5) by the engagement of a stop shoulder 43 on the said sleeve 18 with the upper end 44 of the sleeve 20. In the particular case illustrated, this lowered or sealing position of the outer sleeve 18 is approximately $\frac{1}{8}$ " lower than the mount loading position thereof.

Disposed within the upper end of each spindle 15 is a mount support pin 45 having a head portion 46 overlying and resting on the collar 36 when the latter is in its raised loading position at the loading stations A and B. The upper surface 47 of the mount pin head 46 is of frustoconical shape conforming to but slightly smaller than the conical flare portion 12 of the mount stem 11 so as to provide a slight clearance for permitting a limited amount of lateral adjustment of the lamp mount 9 on the collar 36. The pin 45 extends down into the inner spindle sleeve 19 and has a loose fit therein to allow a limited amount ($\frac{1}{64}$ inch or so) of lateral shifting of the pin in the sleeve. As shown in Fig. 4, the amount pin 45 is provided with a central bore 48 for the accommodation therein of the lead-in wires 13 and the exhaust tube 49 of the lamp mount 9.

Disposed within the inner sleeve 19 immediately beneath the mount pin 45 and reciprocable in said sleeve is a push pin or piston 50 also having a central bore for the accommodation therein of the mount exhaust tube 49. The said push pin 50 is constantly urged upwardly by a soft-acting compression coil spring 51 interposed between a shoulder 52 on the push pin and a shoulder or seat 53 formed in the inner wall of

the sleeve 19. The upward movement of the push pin 50 by the force of the spring 51 is limited by a stop pin or screw 54 fastened to the inner sleeve 19 and projecting into an annular groove 55 in the cylindrical wall of the push pin. The head or outer end portion 56 of the stop pin 54 is received within a vertically elongated slot 57 in the outer sleeve 18 to thereby rotatively lock the inner and outer sleeves 18 and 19 together. The width of the annular groove 55, i. e., the distance between the upper and lower stop shoulders 58 and 59 respectively, is made slightly greater than the diameter of the stop pin 54 so as to permit a very limited amount of reciprocating movement of the push pin 50 relative to the inner sleeve 19. Thus, in the particular case illustrated, the annular groove 55 is made approximately $\frac{1}{16}$ inch wider than the pin 54 to thereby allow approximately $\frac{1}{16}$ inch movement of the push pin 50 relative to the inner sleeve 19.

As shown in Fig. 4 illustrating the spindle parts in their relative positions at the loading stations A and B, the inner sleeve 19 is normally supported within the outer sleeve 18 by the engagement of a stop shoulder 60 on the inner sleeve with a co-operating annular ledge or seat 61 within the outer sleeve. When the inner sleeve 19 is in such position within the outer sleeve 18 with the stop shoulders 60 and 61 in engagement, the upper end 62 of the inner sleeve is spaced a slight distance, for instance $\frac{3}{32}$ inch or so, below the upper surface 63 of the collar 36 at the upper end of the outer sleeve. Also, in such position of the inner sleeve 19 within the outer sleeve 18, the upper end 64 of the spring-lifted push pin 50 is spaced a very slight distance (in the particular case illustrated about $\frac{1}{32}$ inch) from the lower end 65 of the mount pin 45 so that the latter is free to rest on the collar 36.

After a mount 9 and envelope 10 have been properly loaded into a head 2 at the loading stations A and B with the flare 12 resting on the upper surface 63 of the spindle collar 36 and the lower end of the envelope resting on the flare 12, the turret 1 then indexes the head 2 first to idle station C and thence to the first heating station D where the flare 12 and the lower end portion of the envelope 10 are preheated by soft-flame type gas fires (not shown) similar to those fires 66 at the next station E. Just as the head arrives at station D, the pulley 24 at the lower end of the spindle 15 engages the continuously moving belt 25 which then rotates the spindle. The rotational movement of the sleeve 20 on which the pulley is mounted is transmitted to the outer spindle sleeve 18 through a locking key 67 with which the outer spindle sleeve 18 is provided, the said key 67 fitting into a keyway 68 in the inner wall of the sleeve 20. The rotational movement of the outer sleeve 18 is transmitted, in turn, to the inner sleeve 19 through the stop screw 54 the head 56 of which fits within the slot 57 in the outer sleeve.

During the index movement of the head 2 from stations C to D, the lower end 69 of the inner spindle sleeve 19 engages and rides up the tapered front end 70 of an underlying arcuate cam track 71 which is supported on the table 30 and extends from a point approximately midway between stations C and D to a point just before station O. The cam track 71 lifts the inner spindle sleeve 19 to a predetermined "sealing" elevation, and thereafter maintains the inner sleeve at said

elevation from a time just before the spindle arrives at station D until just before it reaches station O when it drops to its normal lowered position once again. In the particular case illustrated, the cam track 71 lifts the inner sleeve 19 a distance of approximately $\frac{3}{32}$ inch to its elevated sealing position.

As the inner sleeve 19 is thus raised by the cam track 71 to its sealing position, the push pin 50 moves bodily upward with the inner sleeve first into engagement with the mount pin 45. This engagement occurs after the first $\frac{3}{32}$ inch of upward movement of the inner sleeve 19 and push pin 50 at which time the upper end 64 of the push pin strikes against the lower end 65 of the mount pin 45. Thereafter, the continued upward movement of the inner sleeve 19 and push pin 50 in unison causes the latter to lift the mount pin 45 until the head portion 46 thereof engages the flare 12 of the lamp mount 9. When this occurs, further upward movement of the mount pin 45 and the push pin 50 is thereafter arrested by reason of the tight grip which the jaws 21', 21" of the holder 21 exert on the lamp envelope 10, such grip being sufficiently firm to hold the envelope from sliding upwardly in the holder under the influence of the lifting force applied to the envelope by the coil spring 51 through push pin 50, mount pin 45, and flare 12. In the particular case illustrated, the engagement of the head 46 of the mount pin 45 with the flare 12 occurs after the mount pin has been lifted off the collar 36 a distance of from .010 to .020 inch (usually around $\frac{1}{64}$ each), depending on the variation in the size of the flare. When the mount pin head 46 thus engages the flare 12, the inner sleeve 19 together with push pin 50 have moved upwardly a total distance of approximately $\frac{3}{64}$ inch, equal to the $\frac{3}{32}$ inch vertical clearance between the push pin 50 and the mount pin 45 plus the $\frac{1}{64}$ inch vertical clearance between the mount pin head 46 and the flare 12. Thereafter, the remaining portion ($\frac{3}{64}$ inch) of the total upward movement ($\frac{3}{32}$ inch) of the inner sleeve 19 is taken up by the coil spring 51 which is compressed between the then stationary push pin 50 and the seat 53 on the upwardly continuing inner sleeve 19. The resulting upward displacement of the inner sleeve 19 relative to the push pin 50 lifts the stop pin 54 a distance of approximately $\frac{3}{64}$ inch off the lower stop shoulder 59 of the push pin, as a result of which the upwardly directed force of the compressed coil spring 51 is then applied to the flare 12 through the push pin 50 and the mount pin 45. The upward spring pressure thus applied to the flare 12 serves to press it into firm engagement with the lower end of the lamp envelope 10 and hold it up at its original loading height as determined by the collar 36 at the loading stations A and B.

Following the preheating of the glass parts at station D, the turret 1 indexes the head 2 to the second heating station E where additional soft-flame type gas fires 66 further preheat the flare 12 and the lower end of the envelope 10.

During the index movement of the head 2 from stations D to E, the tapered rear end 41 of the shoe track 38 allows the outer sleeve 18 to drop until the stop shoulder 43 on the said sleeve 18 abuts against and rests on the seat 44 at the upper end of the spindle sleeve 20. This downward movement of the outer sleeve to its lowered or "sealing" position causes the collar 36 at its upper end to drop away from the flare 12 and so provide a space or passageway through which the

gas fires can enter and heat the flare at points inwardly of its periphery.

From station E, the head 2 is thereafter successively indexed through the several sealing stations F to N inclusive where the exposed rim of the flare 12 and the immediately adjacent lower end portions of the envelope 10 are progressively heated, by very sharp and hard gas fires 72 located at each of said stations, to thereby fuse and seal the said parts together. As the glass of the envelope 10 and flare 12 is progressively softened under the heating effect of the gas sealing fires 72, the upwardly spring-urged mount pin 45 slowly raises the stem 11 until the lower stop shoulder 59 on the push pin 50 engages the stop pin 54. This lifting of the stem 11 by the mount pin 45 tends to counteract any sagging tendency of the softened outer rim portions of the flare immediately inward of the envelope wall, and so facilitates the formation of a strong, sag-free seal between the stem and the envelope.

At the beginning of the index movement of the head 2 away from station J, the shoe 39 on the lower end of the outer spindle sleeve 18 rides up the first of four upsetting or "butt-up" cam tracks 73, 74, 75 and 76 (Fig. 3) mounted on the machine table 30 immediately outward of the cam track 71. The first upsetting cam 73 momentarily lifts the outer sleeve 18 and its collar 36 to a position slightly above (for instance .005 to .010 inch above) its original loading position to thereby straighten out the flare by forcing the sagging rim portion thereof back up to its original position, more or less, with respect to the rigid inner portions of the flare. The second upsetting cam 74, following station K, momentarily raises the upsetting collar 36 to a seal-working position an appreciable height (around .075 inch or so) above its original loading position. This relatively large upsetting movement of the collar 36 presses and works the plastic rim portion of the flare 12 into intimate contact with the edge or rim of the envelope 10, thus positively uniting the said parts together for the first time and, in addition, producing a small annular ridge 77 about the end of the lamp envelope much the same as shown in Fig. 7. The third and fourth upsetting cams 75 and 76 likewise lift the collar 36 a substantial amount (preferably the same as produced by the cam 74) to thereby maintain the plastic glass at the seal up in place at its sealing level and so prevent the formation of a "sagged" and therefore weak seal and also prevent the plastic glass from stretching sufficiently to separate and thus form openings in the seal.

From the last sealing-fire station N, the head 2 is indexed to station O where the finished seal is annealed by soft-flame type gas fires (not shown) located at said stations. During the index movement of the head from stations N to O, the lower end 69 of the inner spindle sleeve 19 rides off the rear end of the cam track 71, thus allowing the said sleeve 19 to drop until the stop shoulder 60 thereon engages and rests on the seat 61 within the outer sleeve 18. This lowering of the inner sleeve 19 to its original loading position causes the mount pin 45 to drop away from the flare portion 12 of the stem 11 and return to its original position resting on the collar 36. The lowering of the mount pin to its original position thus removes the support for the stem which support, however, is no longer necessary inasmuch as the glass at the seal has by that time become sufficiently rigid to support the stem by itself.

After passing through an idle air-cooling sta-

tion P, the head 2 is indexed to the unloading station Q where an operator removes the sealed envelope and mount from the head. During the ensuing index of the head 2 back to the first loading station A, the tapered front end 40 of the shoe track 38 re-engages the shoe 39 on the outer spindle sleeve 18 to raise the mount positioning collar 36 once again to its original loading position preparatory to the placement of another mount 9 thereon.

As shown in Fig. 7, the finished seal produced by the apparatus comprising my invention is characterized by the fact that the flare 12 extends diagonally upward in a substantially straight line right from its rim, while the inner corner between the flare 12 and the wall of the envelope 10 is slightly rounded as indicated at 78. The absence of sag in the flare 12 at the seal, together with the absence of a sharp inner corner between the flare and the envelope, thus results in the formation of a mechanically strong seal capable of withstanding the compressive stresses normally applied thereto by the base which is subsequently attached to the end of the lamp envelope around the seal.

What I claim as new and desire to secure by Letters Patent of the United States is:

1. A spindle for lamp sealing apparatus comprising inner and outer sleeves slidable relative to one another, a pin slidably mounted within an end of said inner sleeve for supporting a lamp mount, said pin having a head portion normally resting against the end of said outer sleeve, and spring means within said inner sleeve normally out of but movable into pressure engagement with said pin.

2. A spindle for lamp sealing apparatus comprising vertically disposed inner and outer sleeves slidable relative to one another, a pin slidably mounted within the upper end of said inner sleeve for supporting a lamp mount, said pin having a head portion normally resting against the upper end of said outer sleeve, and a compression coil spring within and carried by said inner sleeve and being normally out of pressure supporting relation with said pin, said inner sleeve being movable upwardly relative to said pin to thereby lift the spring into pressure supporting relation with said pin.

3. A spindle for lamp sealing apparatus comprising vertically disposed inner and outer sleeves slidable relative to one another, a pin slidably mounted within the upper end of said inner sleeve for supporting a lamp mount, said pin having a head portion normally resting against the upper end of said outer sleeve, a compression coil spring within and carried by said inner sleeve and being normally out of pressure supporting relation with said pin, said inner sleeve being movable upwardly relative to said pin to thereby lift the spring into pressure supporting relation with said pin, and stop means on said inner sleeve between which said spring is initially compressed.

4. Lamp sealing apparatus comprising a carrier having a plurality of heads supported thereon, means for intermittently indexing said carrier to successively advance said heads through a plurality of work stations, each of said heads comprising a holder for tightly gripping and supporting a lamp bulb with an open end down and a spindle for supporting a lamp mount upright in sealing position with the rim of its glass flare abutting against the said open end of the bulb, 75 said spindle comprising a vertically disposed

sleeve, a mount support pin slidably mounted within the upper end of said sleeve and movable upwardly thereof above the engagement position of the pin with the said positioned mount, and spring means compressible between said sleeve and pin to urge said pin upwardly, burners located at certain of said stations for directing gas fires against the contiguous rim portions of the bulb and flare to fuse said portions together, and a cam track at least co-extensive with the travel of the heads through and between the said certain stations and engaging with the said sleeve to continuously compress said spring means against said pin and resiliently press the latter upwardly against the said positioned mount.

5. Lamp sealing apparatus comprising a carrier having a plurality of heads supported thereon, means for intermittently indexing said carrier to successively advance said heads through a plurality of work stations, each of said heads comprising a holder for tightly gripping and supporting a lamp bulb with an open end down and a spindle for supporting a lamp mount upright in sealing position with the rim of its glass flare abutting against the said open end of the bulb, said spindle comprising a vertically disposed sleeve, a mount support pin slidably mounted within the upper end of said sleeve in a position below and normally out of engagement with the said positioned mount, said pin being movable upwardly of said sleeve above the engagement position of the pin with the said positioned mount, and spring means compressible between said sleeve and pin to urge said pin upwardly, burners located at certain of said stations for directing gas fires against the contiguous rim portions of the bulb and flare to fuse said portions together, and a cam track at least co-extensive with the travel of the heads through and between the said certain stations and engaging with the said sleeve to lift the mount support pin into engagement with the mount and continuously compress said spring means against said pin so as to resiliently press the latter upwardly against the said positioned mount.

6. Lamp sealing apparatus comprising a carrier having a plurality of heads supported thereon, means for intermittently indexing said carrier to successively advance said heads through a plurality of work stations, each of said heads comprising a holder for tightly gripping and supporting a lamp bulb with an open end down and a spindle for supporting a lamp mount upright with the rim of its glass flare abutting against the said open end of the bulb, said spindle comprising vertically disposed inner and outer sleeves slidable relative to one another, said outer sleeve being adapted to support the mount at the rim of the glass flare thereof, a mount support pin slidably mounted within the upper end of said inner sleeve and having a head portion normally resting on the upper end of said outer sleeve in a position below and out of engagement with the mount, and spring means compressible between said inner sleeve and pin to urge said pin upwardly, burners located at certain of said stations for directing gas fires against the contiguous rim portions of the bulb and flare to fuse said portions together, a cam track engaging with the said inner sleeve to lift the mount support pin off the outer sleeve into engagement with the mount and to compress said spring means against said pin so as to resiliently press the latter against the mount, and cam means co-operating with the

outer sleeve to momentarily lift and press it against the rim of the glass flare of the mount.

7. Lamp sealing apparatus comprising a carrier having a plurality of heads supported thereon, means for intermittently indexing said carrier to successively advance said heads through a plurality of work stations, each of said heads comprising a holder for tightly gripping and supporting a lamp bulb with an open end down and a spindle for supporting a lamp mount upright with the rim of its glass flare abutting against the said open end of the bulb, said spindle comprising vertically disposed inner and outer sleeves slidable relative to one another, said outer sleeve being adapted to support the mount at the rim of the glass flare thereof, a mount support pin slidably mounted within the upper end of said inner sleeve and having a head portion normally resting on the upper end of said outer sleeve in a position below and out of engagement with the mount, and spring means compressible between said inner sleeve and pin to urge said pin upwardly, burners located at certain of said stations for directing gas fires against the contiguous rim portions of the bulb and flare to fuse said portions together, a cam track engaging with the outer sleeve to support it in an elevated mount-supporting position, another cam track overlapping the first-named cam track and engaging with the inner sleeve to lift the mount support pin off the outer sleeve into engagement with the mount and to compress said spring means against said pin so as to resiliently press the latter against the mount, and cam means co-operating with the outer sleeve to momentarily lift and press it against the rim of the glass flare of the mount.

8. A spindle for lamp sealing-in apparatus comprising a sleeve, support means on said spindle for initially supporting a lamp mount by the rim of its glass flare in a normal sealing position at one end of said sleeve, said sleeve and said support means being relatively movable longitudinally of the sleeve, a mount support pin in said end of said sleeve and slidably therein relative to said support means, said pin having a flare-engageable head portion normally spaced from the flare of the mount positioned on said support means, and spring means within said sleeve and movable thereby into pressure supporting relation with said pin to resiliently urge the head portion thereof against the flare of said mount.

9. In a machine for sealing a flared lamp mount to a bulb neck of smaller diameter than the flare of the mount, a holder for supporting the bulb in neck down position, a vertical spindle located below and in alignment with said holder for supporting the mount upright with its flare abutting against the bulb neck, and means for heating and fusing together the rims of said flare and bulb neck, said spindle comprising a sleeve, a mount pin slidably mounted in the upper end of said sleeve and having a head of smaller diameter than the rim of the flare of said mount whereby to engage the interior of the said flare, and spring means movable within said sleeve from a position normally out of to a position in pressure-supporting relation with said pin to urge the pin upwardly against the mount continuously during the sealing operation.

10. In a machine for sealing a flared lamp mount to a bulb neck of smaller diameter than the flare of the mount, a holder for supporting the bulb in neck down position, a vertical spindle located below and in alignment with said holder

11

for supporting the mount upright with its flare abutting against the bulb neck, and means for heating and fusing together the rims of said flare and bulb neck, said spindle comprising a sleeve, a mount pin slidably mounted in the upper end of said sleeve and having a head of smaller diameter than the rim of the flare of said mount whereby to engage the interior of the said flare, spring means movable within said sleeve from a position normally out of to a position in pressure-supporting relation with said pin to urge the pin upwardly against the mount continuously during the sealing operation, and means independent of said pin arranged to be moved upwardly into engagement with and compress the fused rims of said flare and bulb neck.

11. Lamp sealing apparatus comprising, in combination, a spindle having inner and outer sleeves slidable relative to one another, said outer sleeve being provided at one end with a seating surface adapted to receive the rim of a flared lamp mount, a mount pin slidably mounted within the corresponding end of said inner sleeve, said pin having a head portion partially overlying and engageable with the said seating surface, spring means within said inner sleeve and movable into pressure supporting relation with said pin to urge the pin outwardly of said inner sleeve, cam means coacting with said outer sleeve to move the seating surface thereon into abutting engagement with the head of said pin and move said pin out of pressure supported relation with said spring means, and other cam means for moving said spring means into pressure supporting relation with said pin to thereby move the head of said pin off the said seating surface and resiliently urge it against the lamp mount positioned on the said seating surface.

12. A sealing head for lamp sealing apparatus comprising, in combination, a holder for tightly gripping and supporting a lamp bulb with an open end down, a spindle comprising inner and outer sleeves below and vertically aligned with said holder and slidable relative to one another, said outer sleeve being provided at its upper end with an annular seating surface for supporting a lamp mount upright by the rim of its glass flare, a mount support pin slidably mounted within the upper end of said inner sleeve and having a head portion partially overlying and engageable with the said seating surface, said head portion being of smaller diameter than the flare of the lamp mount and engageable with the interior of the flare of a mount on said seating surface but being spaced downwardly therefrom when the said head portion is seated on said seating surface, and spring means compressible between said inner sleeve and pin to urge said pin upwardly, means for normally holding said outer sleeve in a position to hold a mount thereon with its glass flare

12

abutting against the end of the said bulb and to engage the seating surface on said outer sleeve with the head portion of said pin to thereby hold the pin up out of pressure supported relation with the said spring means, and cam means for moving said inner sleeve upwardly relative to said outer sleeve to move the said spring means into pressure supporting relation with said pin and resiliently press it upwardly against the flare of the lamp mount.

13. A spindle for lamp sealing apparatus comprising vertically disposed inner and outer sleeves slidable relative to one another, a mount pin slidably mounted within the upper end of said inner sleeve for supporting a lamp mount, said mount pin having a head portion normally resting against the upper end of said outer sleeve, a push pin slidably mounted within said inner sleeve beneath said mount pin, and a compression coil spring mounted within said inner sleeve beneath the push pin and compressible between the inner sleeve and said push pin, said inner sleeve being movable upwardly relative to the mount pin to thereby lift the said spring and push pin into supporting engagement with the mount pin.

14. A spindle for lamp sealing apparatus comprising vertically disposed inner and outer sleeves slidable relative to one another, a mount pin slidably mounted within the upper end of said inner sleeve for supporting a lamp mount, said mount pin having a head portion normally resting against the upper end of said outer sleeve, a push pin slidably mounted within said inner sleeve beneath said mount pin, stop means on said inner sleeve engageable with said push pin to limit upward movement of the push pin relative to the inner sleeve and to hold the push pin in a normal position out of supporting engagement with said mount pin, and a compression coil spring mounted within said inner sleeve beneath the push pin and compressed between the inner sleeve and said push pin, said inner sleeve being movable upwardly relative to the mount pin to thereby lift the said spring and push pin into supporting engagement with the mount pin.

HENRY W. JACOBSEN.
